UNITED STATES PATENT OFFICE

149,317

DESIGN FOR A SANDWICH TRAY OR SIMILAR ARTICLE

Lenore Sonn, New Haven, Conn.

Application May 23, 1946, Serial No. 130,025

Term of patent 7 years

(Cl. D44—10)

To all whom it may concern:

Be it known that I, Lenore Sonn, a citizen of the United States, residing at New Haven, in the county of New Haven and State of Connecticut, have invented a new, original, and ornamental Design for a Sandwich Tray or Similar Article, of which the following is a specification, reference being had to the accompanying drawing, forming part thereof.

Fig. 1 is a plan view of a tray showing my new design.

Fig. 2 is a cross-sectional view taken through the center of the tray shown in Fig. 1.

Fig. 3 is a perspective view of the tray shown in Fig. 1.

I claim:

The ornamental design for a sandwich tray or similar article as shown.

LENORE SONN.
